UNITED STATES PATENT OFFICE.

CHARLES E. POPE, OF MILLVILLE, ASSIGNOR, BY DIRECT AND MESNE ASSIGNMENTS, TO HIMSELF, AND WILLIAM SCROGGIN, OF BEARDEN, ARKANSAS.

ROOFING.

SPECIFICATION forming part of Letters Patent No. 508,751, dated November 14, 1893.

Application filed March 25, 1893. Serial No. 467,608. (No model.)

To all whom it may concern:

Be it known that I, CHARLES E. POPE, of Millville, in the county of Ouachita and State of Arkansas, have invented new and useful 5 Improvements in Roofing, of which the following is a specification, reference being had to the annexed drawings, forming a part there- of, in which—

Figure 1 is a perspective view of a portion 10 of a roof constructed according to my im- provement. Fig. 2 is an enlarged transverse section, and Fig. 3 is an enlarged transverse section of a single roof portion.

Similar letters of reference indicate corre- 15 sponding parts in all the views.

The object of my invention is to construct 20 a simple and efficient roof at low cost, and one that may be readily applied and which is capable of being covered with roofing ma- terial such as metal or felt.

My invention consists in the construction 25 hereinafter described and claimed.

The board A, of which the roof is made, is provided upon one edge with a groove a, 30 whose lower or under wall is of less width than its upper or outer wall and upon the opposite edge with a tongue b, of a greater width on its upper side than on its lower to fit into the groove of the adjacent roof board. 35 The material of the board above the groove a projects beyond the portion lying below the said groove, and the rabbet above the tongue b on the opposite edge of the board is tapered beyond the rabbet below the tongue so that 40 the groove and the portions of the board above and below the groove fit the tongue and the portions of the edge of the board above and below the tongue, so as to form a tight joint. In the upper surface of the tongue b adjoining 45 the body of the board is formed a groove c, to receive any water that may leak through the joint between the edges of the adjacent boards. In the top of the board adjoining opposite edges are formed shallow channels 50 d, which incline downwardly away from the

joint, and in the central portion of the board is formed a shallow channel e, the sides of which incline downwardly from the inner borders of the channels d to the center of the board. It will thus be seen that the water falling on the roof, instead of being allowed to flow freely to the joints of the roof boards, is conveyed away by the inclined surfaces of the channels, and that any water leaking through the joints between the boards is con- 55veyed away by the grooves in the upper sur- faces of the tongues.

A roof constructed according to my im- provement requires but a single layer of 60 boards, and it may at any time be covered by sheet metal, by felt, or by roofing paper, thus affording a double protection, since any water finding its way through leaks in the covering laid on the boards will be conveyed away and cannot find its way through the 65 roof.

Having thus described my invention, I claim as new and desire to secure by Letters Patent—

As an improved article of manufacture a 70 roofing board A, provided in one edge with a groove a, the lower or under wall of which is of less width than its upper or outer wall, and upon its opposite edge with a tongue b of a greater width on its upper side than on 75 its lower to properly fit an opposed groove a, the upper face of the tongue being provided with a groove c, side channels d d and a cen- tral shallow channel e in the upper face of the board the sides of which channel incline 80 downwardly and inwardly from the inner borders of the two side channels d, which lat- ter channels incline downwardly away from the edges of the board, substantially as set forth.

CHARLES E. POPE.
